UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-PLATE-MOLDING APPARATUS.

Application filed April 6, 1925. Serial No. 21,054.

This invention is a novel improvement in molding apparatus, and is especially adapted for use in the casting or molding of so-called stereotype plates used in printing presses. The object of the invention is to provide a novel gate for pouring metal into a mold whereby the inflowing metal is divided at the point of inlet, and flows in opposite directions into the mold so as to shorten the travel of the metal in the mold chamber and more quickly fill the same, as compared with the present known apparatus in which the metal has to traverse the entire length of the mold chamber in filling the same.

This invention is especially designed for use in connection with stereotype plate casting boxes; and in the particular embodiment of the invention illustrated in the drawings is used in connection with boxes for casting so-called tubular stereotype plates.

By using this invention the metal enters midway of the mold chamber rather than at one end thereof; and preferably also enters the mold chamber through an inlet in the top thereof rather than at one side thereof, but I do not consider the invention limited to any particular position of the pouring slot or gate, provided that in any case the gate be so constructed and located that the molten metal passing into the mold from such gate is divided into jets or streams which flow in opposite directions into the mold chamber; thereby greatly facilitating the filling of the mold, lessening the liability of the metal to chill or harden before the mold chamber is completely filled, and expediting the filling of the mold chamber.

I will explain the invention with reference to the accompanying drawings, an understanding of which will enable others to adopt and use the invention in connection with different kinds of casting boxes or molds. In the claims the essentials of the invention and novel features of construction and novel combination of parts, for which protection is desired, are summarized.

In said drawings—

Figure 1 is a detail side view of a casting box including a drag, cope, and core; equipped with a novel pouring gate in accordance with this invention.

Figure 2 is an end view of Figure 1, showing the box closed in full lines; and partially open in dotted lines.

Figures 3 and 4 are enlarged vertical transverse sections through the pouring gate and adjacent parts of the box, showing the alternate arrangement of the passages for the entry of the inflowing metal into the 60 mold chamber.

Figure 5 is a top plan view looking downward.

Figure 6 is a longitudinal section on the line 6—6 Figure 3; indicating a slight modification of the construction of the gate.

Figure 7 is an enlarged section on the line 7—7, Figure 3, showing the arrangement of the passages for the entry of the inflowing metal into the mold chamber.

The casting box is only partially shown as the present invention relates to the pouring gate rather than to any particular construction of the box, which may be varied. As shown, the box has a drag 1, a cope 2, 75 a core 3, and a pouring gate 4.

In the box shown, the end of the core 3 is adapted to extend between the cope and drag when the parts are in casting position as in Figures 1 and 2, and the cope and drag 80 each have a semi-cylindric recess in their opposed faces adapted to closely fit around the core when the box is closed; and the drag and cope have semi-cylindric chambers (1^a, 2^a) in their opposed faces which, 85 when the cope and drag are closed around the core, together form an annular mold chamber C, indicated in dotted lines in Figures 1 and 2, in which the plate is cast. The drag and cope are preferably hinged together at the lower side, as indicated at 1^b, and they may be held in closed position around the cope by any suitable means not shown, such means not forming any part of the present invention.

The gate 4 communicates with the chamber C through a longitudinal slot or mouth, which is preferably formed between the free meeting ends of the drag and cope. Preferably the gate consists of two opposed side 100 plates 4^a, 4^b, and a plurality of interposed vertical partitions or members 4^c.

When the box is closed the opposed faces of the plates 4^a, 4^b slightly converge, forming an approximately wedge shaped mouth, 105 and preferably one of the plates as 4^b extends above the top of the adjacent plate so as to facilitate pouring the metal through the spout S of any suitable melting pot into the mouth. The inner ends of the plates 110

^{4a, 4b} are adapted to contact with the surface of the core ³ and in the form of a box shown will practically produce a longitudinal slot in the tubular plate cast therein, which plate is substantially like the plate described in my Patent No. 1,129,946, dated March 2, 1915.

The partitions ^{4c} are spaced apart and preferably equidistant and parallel. These ¹⁰ partitions and their distances apart may be varied to suit. In the particular example shown there are thirteen such partitions, the two outer ones forming the end walls of the gate. These partitions are adapted to extend transversely across the mouth and extend from a point at a sufficient distance below the top of the shorter plate ^{4a} to the inner edge of the plate; i. e., to a point of contact with the core ³ when the box is closed.

²⁰ These partitions may be formed integral with the plate ^{4a} or the plate ^{4b} or partly formed on one plate and part on the other. As indicated in Figure 5 the partitions are all formed on the inner face of the short plate ^{4a}. As indicated in Figure 6 every other partition is formed on the plate ^{4a} and the intermediate partitions are formed on the plate ^{4b}. The partitions may be cast with the plates or may be cast separately and fastened thereto by any suitable means.

As shown the said partitions divide the gate into a series of vertical ducts ^D, and the alternate ducts ^D communicate at their lower ends alternately with opposite sides of the chamber ^C. For example every alternate duct ^D will communicate with the left hand side of the chamber ^C through a passage ^{4s} in the lower edge of the plate ^{4a}, for example, (see Figures 3, 5, 6) and all the ⁴⁰ intermediate ducts ^D will communicate with the opposite side of the chamber ^C through passages ^{4t} in the lower end of the edge of the plate ^{4b} as indicated in Figures 4, 5 and 6.

⁴⁵ With this construction when the box is closed and in casting position, as indicated in Figures 1 to 4, the molten metal poured into the mouth will flow through the various parallel ducts ^D toward the chamber ^C, but ⁵⁰ part of the metal is directed into the left hand side of the cylindric mold chamber through the passages ^{4s} in the lower edge of plate ^{4a}, and part of the metal is directed into the right hand side of the mold chamber ^C through the passages ^{4t} in the lower edge of the plate ^{4b}. Thus the metal flows ⁵⁵ into the chamber in opposite directions around the core, and the streams of metal meet at the center of the chamber, and the mold chamber will be quickly filled as the metal only has to travel one half the circumference of the core, or one half the total length of the mold chamber to fill the chamber; whereas in the present forms of tubular plate casting boxes the metal enters the ⁶⁰ mold chamber from one end only and has to flow the entire length of the chamber in order to fill it.

The plates ^{4a, 4b} are respectively attached to the free meeting ends of the cope ¹ and drag ² as shown and might be formed integral therewith, but I prefer to form the plates ^{4a} and ^{4b} separately and secure them to the meeting end faces of the drag and cope, as indicated in the drawings, as this facilitates machining of the plates. As shown the plate ^{4a} is secured to the meeting face of the drag ¹ by bolts ^{1e} set in suitable recesses in the drag and tapped into the plate ^{4a}. The plate ^{4b} is similarly shown as attached to the cope ² by bolts ^{2e}. Obviously any other suitable means of fastening plates to the cope and drag may be employed.

Of course metal could be supplied to the gate by a ladle instead of by a spout, as the means of getting the metal to the gate is not a part of the invention, but the metal supplied to the single gate is divided at the point of entry into the mold into a number of small jets, which preferably enter the mold chamber in opposite directions, and as these openings ^{4s} and ^{4t} connect the mold chamber with alternate ducts between the ribs, approximately half the metal would flow into the mold chamber to the right, and half would flow into the mold chamber to the left, quickly filling the mold chamber as stated.

I claim:

1. A mold provided with a pouring gate ¹⁰⁰ having a plurality of ducts whereby the metal is divided into a plurality of oppositely flowing jets as it enters the mold-chamber.

2. A casting box having a molding chamber and a pouring gate provided with a plurality of inlet passages whereby the metal is divided into a plurality of oppositely flowing jets as it enters the molding chamber.

3. A casting box having a molding chamber and a gate provided with a plurality of partitions whereby the gate is divided into a plurality of ducts by which the metal is divided and enters the molding chamber in opposite directions.

4. A casting box having a molding chamber and a gate having a plurality of ducts communicating with the chamber whereby the metal is divided into a plurality of oppositely flowing jets as it enters said chamber.

5. A casting box having a cope and a drag; and a gate provided with a series of oppositely opening ducts whereby the metal is directed into the chamber at a plurality of ¹²⁵ points.

6. A casting box having a cope, and a drag; and a gate communicating with the molding chamber of the box and provided with alternate passages opening from the ¹³⁰

gate into the molding chamber at opposite sides of the gate.

7. A casting box having a cope and a drag; and a pouring gate having a plurality of ducts, communicating with the mold chamber at opposite sides of the gate, whereby the metal is divided and directed into the chamber in opposite directions.

8. A casting box having a cope, and a drag; a gate divided into a plurality of ducts, and passages connecting different ducts with the mold chamber at opposite sides of the gate, whereby the metal is directed into the molding chamber in opposite directions at a plurality of points.

9. A casting box having a cope, and a drag and a core; and a gate communicating with the molding chamber through passages opening into the mold chamber at opposite

sides of the gate, whereby the metal is di-

rected into the molding chamber in opposite directions at a plurality of points.

10. A casting box having a cope, a drag and a core; and a gate having a plurality of ducts; and passages connecting different ducts with the mold chamber at different sides of the gate, whereby metal is directed into the molding chamber in opposite direction.

11. A casting box having a cope, a drag, and a core; and a gate having partitions dividing it into a series of ducts; and passages from alternate ducts opening into the molding chamber at opposite sides of the gate, whereby metal is directed into the molding chamber in opposite directions at a plurality of points.

In testimony that I claim the foregoing as my own, I affix my signature.

HENRY F. BECHMAN.
